UNITED STATES PATENT OFFICE.

JACOB FELBEL, OF NEW YORK, N. Y., ASSIGNOR, BY MESNE ASSIGNMENTS, TO REMINGTON TYPEWRITER COMPANY, OF ILLION, NEW YORK, A CORPORATION OF NEW YORK.

TYPE-WRITING MACHINE.

1,083,526.

Specification of Letters Patent.

Patented Jan. 6, 1914.

Application filed May 5, 1908. Serial No. 430,930.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to devices for controlling the work sheets.

One object of the invention is to provide simple and efficient means for properly controlling and handling the sheets in doing condensed record work.

15 A further object of the invention is to provide devices in the nature of attachments which may be readily applied to existing 20 styles of typewriting machines without modifying the structural features of said machines.

To the above and other ends, which will hereinafter appear, my invention consists in 25 the features of construction, arrangements of parts and combinations of devices to be hereinafter described and particularly pointed out in the appended claims.

In the accompanying drawings, wherein 30 like reference characters indicate corresponding parts in the various views, Figtre 1 is an enlarged detail fragmentary front elevation with parts omitted and parts broken away of one form of a typewriter carriage 35 embodying my invention. Fig. 2 is a vertical transverse sectional view of the same, the section being taken on the line $w-w$ of Fig. 1 and looking in the direction of the arrow at said line. Fig. 3 is an enlarged 40 detail fragmentary sectional view of some of the parts shown in Fig. 2, the section being taken on the line $x-x$ of Fig. 2 and looking in the direction of the arrow at said line. Fig. 4 is an enlarged detail vertical 45 sectional view taken longitudinally of the platen and showing a modified structure embodying my invention. Fig. 5 is an enlarged detail side elevation with parts in section of a still further modification embodying my invention. Fig. 6 is an enlarged 50 detail sectional view of the parts shown in Fig. 5, the section being taken on the line $y-y$ of Fig. 5. Figs. 7 and 8 are

detail perspective views of some of the parts shown in Figs. 5 and 6.

At times invoice or bill sheets are employed which are wider than the condensed record or journal sheets and in some instances the ruling of the invoice and condensed record or journal sheets is the same, 60 considered with reference to the right-hand edges of the sheets though the invoice sheets have a wider left-hand margin. In such cases, in order to bring the ruling on the invoice and record sheets in register, it is necessary to extend the left hand margin of the invoice sheet laterally beyond the record sheet while the sheets are being written upon in the machine.

One of the objects of my present invention 70 is to provide devices which will properly handle sheets thus assembled and also properly take care of the paper when the record sheets are either of a width equal to or greater than the width of the invoice sheets, 75 all as will hereinafter more clearly appear.

In the present instance I have shown my invention embodied in the Monarch type-writing machine.

The platen frame or carriage comprises 80 end plates 1 and a rear connecting cross or slide bar 2, the latter being provided with oppositely disposed grooves 3 for coöperation with anti-friction balls or rollers and grooved rails (not shown) by which the carriage is supported to travel from side to side of the machine over the top plate. A platen shaft 4 is journaled in the end plates 1 of the carriage and is provided with the usual finger wheels (not shown). A rotative cylindrical platen 5 is secured to the platen shaft 85 in the usual manner. The usual line spacing mechanism (not shown), paper feed rollers 6 and 7 and, paper table 8 are provided. A cross bar or rod 9 is rigidly connected at its ends to the end plates 1 of the carriage and extends over the platen and constitutes a support for sleeves 10 which are splined to the rod at 11 so that the sleeves cannot turn on the supporting rod 90 95 but may be adjusted longitudinally thereof. Each of these sleeves carries a rigid arm 12 to which a spring-pressed hanger 13 for a paper feed roller 14 is pivoted at 15. A spring-pressed paper finger 16 is also pivoted at 17 to each arm 12. From an inspec-

tion of Fig. 1 it will be observed that the paper fingers 16 are each apertured at 18 to enable its associated feed roller 14 to protrude therethrough and contact with the platen or the paper thereon. It will also be observed that the paper fingers and feed rollers are off-set inwardly from their supporting arms 12.

A sheet metal plate or bar 19 is provided with eyes 20 which surround circumferential depressions in the supporting rod 9, the eyes forming hinges between the rod and plate. The weight of the plate maintains the forward edge thereof in contact with the platen as indicated in Fig. 2 so that in use the plate always remains fixed relatively to the platen frame. In the present instance the plate 19 constitutes an erasing plate which extends substantially throughout the length of the platen.

From an inspection of Figs. 1, 2 and 5 it will be seen that each of the splined supporting sleeves 10 at the cut-out therein overlaps the erasing plate 19 and prevents or limits a swinging movement of the plate on its pivot when the sleeves are in the positions they ordinarily occupy along the rod 9.

The constructions thus far described are common to the Monarch machine and further detailed description thereof is deemed unnecessary.

Holding or clamping fingers, members or devices each designated as a whole by the reference numeral 21, are preferably mounted for adjustment longitudinally of the platen. In the present instance each clamping member is arranged above the platen and is pivoted at 22 to an arm 12, the pivotal axis of the clamping members extending transversely of the platen so that said members are pivoted to swing toward and away from the platen in a plane which cuts through the platen longitudinally thereof. Each clamping member comprises an engaging or pressing portion 23 which projects inwardly from the pivot toward the center of the platen, and when in engaging position the part 23 extends parallel with the axis of the platen and parallel with the plate 19. Each clamping member preferably has angular bends 24, 25 and 26, the part 26 constituting a finger piece by which the clamping member may be turned on its pivot to operative and inoperative positions. Ears 27 are formed on the portion 25 of each clamping member, said ears being perforated for the reception of the pivot pin 22 which is connected at its ends to arms 29 of a substantially U-shaped bracket secured to a base plate 30, which in turn is secured by screws 31 to the upper side of the arm or support 12. A spring 32 is secured at one end by rivets 33 to the base 30 of each bracket and these rivets also connect the U-shaped member to its base plate 30. The

free end of the spring is adapted to bear against either of the portions 25 or 26 of the clamping member, depending on the position of the clamping member; thus, when the clamping member is in the operative position shown in full lines in Fig. 3 the spring 32 co-operates with the part 25 and tends to maintain the clamping device in the operative position, that is, with the portion 23 of the clamping member under pressure against the plate 19 or the paper thereon. When the clamping member is turned on its pivot to the inoperative position, shown in dotted lines in Fig. 3, the spring 32 co-operates with the part 26 to maintain the clamping member in such position. The construction of each of the clamping members, paper fingers, feed roller 14 and the supports therefor is the same, except that the clamping members project in opposite directions and the description of one of the clamping members and associated parts applies equally to the other. The construction is such that the feed rollers 14 and paper fingers 16 co-operate with the paper at the opposite side edge portions thereof in the usual manner.

In the use of the devices for condensed record billing work, the sleeves 10 and the parts carried thereby may be adjusted longitudinally of the platen in order that the feed rollers and paper fingers may properly co-operate with work sheets of the width to be employed. From an inspection of Fig. 1 it will be seen that the condensed record sheet 100 a which lies next to the platen, is of less width than the invoice sheet b and is of a width materially less than the length of the platen; the interposed carbon sheet c preferably being of a width which corresponds to the record sheet. It will also be seen that the rulings d and e on the record and invoice sheets, respectively, register when the right-hand edges of said sheets are brought into register, so that the items or amounts 110 written within the respective columns upon the invoice sheet will be reproduced through the interposed carbon or transfer sheet in corresponding columns on the record or journal sheet. The sleeves 10 and the parts carried thereby may be adjusted substantially in the manner shown in Fig. 1 so that the parts will bear a relation to the sheets widthwise thereof such as that indicated in said figure. The clamping members are first turned to the inoperative position shown in dotted lines in Fig. 3 and the record sheet, invoice sheet and interposed carbon sheet are introduced simultaneously into the machine with the record sheet next to the platen and the invoice sheet outermost where it will receive the impacts of the types. The leading edges of the sheets may coincide or a "lead" of the invoice sheet may be given in the usual man-

ner so that the first line on the record sheet may appear near the top thereof. All three sheets pass beneath the right-hand paper finger and feed roller 14 and all of said 5 sheets may pass beneath the left-hand paper finger and feed-roller 14 or the left-hand paper finger and feed roller may bear against the invoice sheet only, depending on the relative widths of the sheets, or other 10 circumstances. After the leading edges of the sheets pass the paper fingers and feed rollers 14 they leave the platen and feed or pass over the plate 19 and supporting bar 9. When the platen has been turned so that 15 the invoice sheet is in a position to receive the first line of writing, the operator proceeds to fill in the invoice which is duplicated on the record sheet. The platen may then be given a double line space to provide 20 a proper space between the copies of the different bills on the record sheet. The invoice sheet is then raised or its free portion pulled forwardly and the clamping members then turned down into operative position 25 with the holding portion 23 between the invoice and carbon sheets and so as to bear against the carbon and record sheets. In other words, the engaging portions, fingers or blades of the clamping members are inserted 30 between the invoice and carbon sheets and caused to bear against the carbon sheet so as to press it and the record sheet against the erasing plate 19 and hold the last mentioned sheets against movement while the 35 completed invoice sheet is removed from the machine. This removal may be accomplished by throwing and locking off the feed rollers 6 and 7, and 14 if used, and pulling on the invoice or outer sheet alone. After 40 the removal of the invoice, a new invoice sheet is introduced into the machine while the platen, record and carbon sheets remain fixed or stationary. When the newly introduced invoice sheet has been properly 45 adjusted to receive the first line of writing the feed rollers are unlocked or restored to writing position and the clamping members are turned to the inoperative position to release the carbon and record sheets and the 50 operator proceeds as before to fill in the invoice which is duplicated on the record sheet. When the second bill is completed the operator proceeds as before and so on until the record sheet has been filled when 55 a new record sheet may be introduced with a bill and carbon sheet as before.

While I have described one method of using the devices for condensed record work it should be understood that this method 60 may be varied. For instance, it may be found desirable to use comparatively short carbon sheets of the same width as the invoice sheets employed. In this event the carbon sheet may be removed with each invoice sheet as it is filled in and the clamp-

ing device or devices instead of bearing on the carbon and record sheets will bear only on the record sheet so as to clamp said record sheet while the invoice and carbon sheets are removed.

The introduction and proper positioning and removal of the invoice sheets are not substantially different from what would be the case were the condensed record method not employed, except that the platen is not turned either to introduce, position or remove the successive invoice sheets. The casting off of the feeding devices leaves a clear passage for the introduction, adjustment and removal of the invoice sheets while the record sheet remains held to the platen. Thus there is no liability of disturbing the record sheet during these operations.

From the foregoing description it will also be observed that the devices are simple in construction, easy of operation, inexpensive to manufacture and may be readily applied to existing machines without substantial change therein.

While I have shown the use of two clamping devices 21, each adjustable longitudinally of the platen with the carrier for the paper finger 16 and the feed rollers 14, it should be understood that only one of these 95 clamping devices may be found necessary.

In Fig. 4 I have shown a modified construction of my invention in which the clamping member is made of two relatively adjustable parts, the parts being united by a screw 34 which passes freely through a slot 35 in one member and enters a tapped hole in the other member. By this construction I am enabled to effect a relative adjustment between the two parts of each clamp in order that the engaging or pressure member 23^a thereof may efficiently engage the paper and with the desired pressure. In this construction I have shown the clamping member co-acting with the top of the platen 5 instead of with the plate 19, as in the construction previously described. It may be found desirable in some instances to cover the engaging portion of the clamp with a sheath of soft rubber or like material 36, in order better to grip and hold the carbon and record sheets against movement. I have also shown in Fig. 4 a different form of spring means for retaining the clamping device in either the operative or inoperative position. Thus, a headed plunger 37 works in an opening 38 in the arm 12^a on which the clamping member is pivotally supported. A coiled expansion spring 39 surrounds the plunger and bears at one end against the head of the plunger and at its opposite end against the supporting arm 12^a. By this construction the head of the spring pressed plunger bears against the part 25^a or 26^a of the clamping member to 130

hold the member either in the operative or inoperative position; and to exert the pressure on the clamping member to hold it under pressure when it is in the operative position. The arm 12^a in this construction corresponds to the arm 12 in the construction previously described and the operation of the device, shown in Fig. 4, is the same as in the construction previously described. The features shown in Fig. 4 may of course be incorporated in the form shown in Figs. 1-3.

In Figs. 5 and 6 I have shown a still further modification of the construction in which the devices do not extend so high as in the previously described constructions. Thus, a sheet metal bracket 40, which is shown in detail in Fig. 7, is secured by screws 41 to the supporting arm 12^a of a paper finger 16 and feed roller 14. This bracket embraces the arm 12^b and is provided with ears 42 by which a pivot pin 43 is supported, said pin passing freely through openings in ears 44 struck up from a sheet metal clamping member, which is shown in detail in Fig. 8, so as to provide a pivotal support for said clamping member. A spring 45 is secured at one end, as at 46, to the bracket 40 and the free end of said spring bears either against a face 47 or a face 48 of the clamping member so as to retain it either in the operative or inoperative position as desired. The free end of the clamping finger 49 is slightly upturned as at 50 to provide a finger piece or means whereby the clamping member may be lifted out of engagement with the plate 51 (or the platen if the plate be not used) and turned to the inoperative position. In Fig. 6 the paper is not illustrated for convenience. The paper fingers, feed roller and arm 12^b are constructed and mounted upon the supporting bar 9^a as in the construction shown in Figs. 1, 2 and 3. The operation of the devices shown in Figs. 5 and 6 is essentially the same as in the construction shown in Figs. 1, 2 and 3 and need not be repeated.

It will be noted that the pile or set of superposed work sheets is fed into the platen over the paper table 8 and between the feed rollers 7 and 6 and the platen, and between the paper fingers 16 and the platen, and between the feed roller 14 and the platen, (if the feed roller 14 be used, and that, in the course of the writing, the platen is line spaced step-by-step as usual and the paper discharged from the platen upwardly and rearwardly over the plate or bar 19, which, with the clamping member, is situated over the platen and on the discharge side thereof. In the present construction and in the Monarch machine the printing point is at the front side of the platen and opposite the head of the arrow α shown at Fig. 2. By locating the record-sheet clamping device

above the platen and on the discharge side thereof, it will be observed that the record sheet may be controlled and written upon down to the very bottom edge, which is not the case where the clamping device is arranged on the introductory side of the platen. It will be observed, furthermore, that the clamping device herein is a clamp or sheet holding contrivance purely; that is to say, that it does not in any manner assist in the feeding of the paper; on the contrary, is directly opposed to a feeding operation and is independent of the paper feed mechanism. Therefore where the term "clamp" or "sheet holding contrivance" or the like is employed it is to be construed as something different from a paper feeding device and as opposed thereto.

It will be understood that in the Monarch billing or condensed record machine, means are provided for simultaneously casting off the feed rollers 7 and 6 and the paper blade or scale bar (not shown), and in some instances also the paper fingers 16; and in consequence of this arrangement or provision in the machine the billing or invoice sheet, which is usually the outside sheet of the pile, may be readily removed from the machine while the sheets underneath are by means of my novel device held clamped either directly upon the platen or directly upon the erasing plate 19; and while the feeding mechanism is thus cast off the new bill or outside sheet may be readily introduced from the rear of the machine and brought to proper position with reference to the sheets underneath, whereupon the feeding devices are released or brought back into coöperation with the paper on the platen and the clamp is turned to an inoperative position.

It is not always necessary that the clamp, in normal position, stand in the dotted line position shown at Fig. 3. It may lie in direct contact with the erasing plate and all of the paper may be fed thereover; then when it may be desired to clamp the record sheet and its superposed carbon, if necessary, all of the sheets may be pulled forwardly toward the operator; then the top or outside sheets are separated, the clamp swung up to the dotted line position in Fig. 3, the record sheet and its carbon laid upon the erasing plate and then the clamp may be swung down to hold the last two mentioned sheets only, leaving the outside sheet free. Then the paper feeding devices may be thrown off and the free sheet removed. After the introduction of another bill sheet the clamp may be raised to release the under sheet and at this time it may be tucked under the record sheet against the erasing plate or it may be left upstanding in accordance with the desire of the operator. It will also be noted that the pile of paper to be written

upon is introduced between the paper table and the clamp, and so that the clamp cannot be used in connection with the paper until the paper shall have been fed past the printing point and shall have been advanced far enough to be emerging from the machine.

It will be seen that in all of the constructions shown the clamping members are pivoted at their outer ends so that the pivot and support for each member are arranged laterally beyond or outside the side edges of the sheets employed in the machine; that each of the clamps is hand operated; that the work sheet holding device shown in Fig. 4 coöperates with the platen to hold the sheets thereon, whereas the clamping devices shown in the remaining figures coöperate with the plate 19 or with means independent of the platen, and that in all forms shown certain of the sheets pass over the engaging portions of the clamping devices and certain other of the sheets lie under such engaging portions of the clamping devices.

Various changes may be made without departing from the spirit and scope of my invention.

What I claim as new and desire to secure by Letters Patent, is:—

1. In a typewriting machine, the combination of a platen, paper feeding devices, and clamping means separate from said paper feeding devices, said clamping means being arranged on the discharge side of the platen and adapted to coöperate with one or more sheets and hold the same during the removal of another superposed sheet; said clamping means being inactive during paper feeding and writing operations and brought into service only when it is desired to remove a superposed sheet.

2. In a typewriting machine, the combination of a platen, and clamping means which coöperate with one or more of a set of superposed sheets, one narrower than the other, the clamping means being insertible under the outer sheet and coöoperative and engageable with the narrow under sheet or sheets so that the wider outer sheet may be removed while the sheet or sheets between it and the platen are held against movement; said clamping means being inactive during paper feeding and writing operations and brought into service only when it is desired to remove a superposed sheet.

3. In a typewriting machine, the combination of a rotative platen, paper feeding devices, and a clamping device separate from said paper feeding devices, said clamping device being adjustable longitudinally of the platen and insertible between the sheets of a set of superposed sheets and operative to hold those beneath while the other or others of said set are removed; said clamping means being inactive during paper feeding and writing operations and

brought into service only when it is desired to remove a superposed sheet.

4. In a typewriting machine, the combination of a rotative platen, paper feeding devices and a clamping device separate from said paper feeding devices, said clamping device being coöoperative with the work sheets on the discharge side of the platen and operative to hold one or more of a set of superposed sheets during removal of the outside sheet or sheets; said clamping means being inactive during paper feeding and writing operations and brought into service only when it is desired to remove a superposed sheet.

5. In a typewriting machine, the combination of a rotative platen, paper feeding devices, and a normally free paper clamping device separate from said paper feeding devices, said clamping device being arranged on the discharge side of the platen and movable at the cessation of the feeding and writing operations to clamp one or more of a set of superposed sheets after they leave the printing point to hold the same against movement while another of said superposed sheets is removed.

6. In a typewriting machine, the combination of a rotative platen, a platen frame, a bar carried by the platen frame and which when in use remains fixed relatively to the platen frame and over which the paper is fed as it is discharged from the platen, and a clamp coöperating with said bar only to hold one or more of a set of superposed sheets on the platen during removal of another or others of said sheets.

7. In a typewriting machine, the combination of a rotative platen, a platen frame, a bar carried by the platen frame, a clamp adjustable longitudinally of the platen and coöperating only with said bar to hold one or more of a set of superposed work sheets during the removal of one or more other work sheets of said set.

8. In a typewriting machine, the combination of a rotative platen, a bar on the platen over which the paper passes as it leaves the platen, and a clamp coöperative with said bar to hold one or more under sheets on the platen during the removal of the outer sheet or sheets.

9. In a typewriting machine, the combination of a rotative platen, a bar arranged on the discharge side of the platen and over which the paper passes as it leaves the platen and a record sheet clamp adjustable longitudinally of said platen and bar and coöperative with said bar.

10. In a typewriting machine, the combination of a rotative platen, a clamping finger arranged at the discharge side of the platen to act on the leading portion of one or more of a pile of sheets after printing and which when not in use is maintained

- free of the platen and which when in use projects longitudinally of the platen and inwardly from its support, and means coöperating with said clamping finger to hold 5 one or more sheets against movement while an outside sheet is being removed.
11. In a typewriting machine, the combination of a rotative platen, a support adjustable longitudinally thereof, a clamping 10 finger which when not in use is maintained free of the platen and which when in use projects longitudinally of the platen and inwardly from said support, and means coöperating with said clamping finger to hold 15 one or more of a pile of superposed sheets against movement during removal of one or more of such sheets.
12. In a typewriting machine, the combination of a rotative platen, a platen frame, 20 a bar carried by the platen frame at the discharge side of the platen and which when in use remains fixed relatively to the platen frame, and a clamping finger that is manually movable into and out of contact with 25 the leading ends of certain of said work sheets in the machine to clamp the same against said bar.
13. In a typewriting machine, the combination of a rotative platen, a platen frame, 30 a bar carried by the platen frame over said platen and which when in use remains fixed relatively to the platen frame, means for feeding a pile of sheets over said bar, and a spring-pressed clamping finger that is pivoted to swing in a plane at substantially 35 right angles to the direction of feed of said sheets over said bar.
14. In a typewriting machine, the combination of a rotative platen, a platen frame, 40 a bar carried by the platen frame over said platen, a clamping finger that is movable into and out of contact with said bar and adapted to clamp one or more sheets in the machine against said bar while another or 45 other sheets are removed, and means for enabling an adjustment of said clamping finger longitudinally of the platen.
15. In a typewriting machine, the combination of a rotative platen, a paper feeding 50 device coöoperative with the platen, a support therefor, a clamping member carried by the support for said paper feeding device and at all times maintained out of coöperation with the platen, means coöoperative with 55 said clamping member to hold one or more of a set of superposed sheets against movement while one or more of said set are being removed, and means for enabling a simultaneous adjustment of the paper feeding device and clamping member longitudinally 60 of the platen.
16. In a typewriting machine, the combination of a rotative platen, a platen frame, a rod carried by the platen frame and situated 65 above the platen, a paper finger carried by said rod and adjustable longitudinally of the platen, said paper finger coöperating with the platen, a spring-pressed pivoted record-sheet clamping member carried by the support for said paper finger and adjustable longitudinally of the platen with the paper finger, and means independent of the platen and coöperative with said clamping member. 70
17. In a typewriting machine, the combination of a rotative platen, a pivoted record-sheet clamping member extending longitudinally of the platen and having its pivot arranged transversely of the platen, and means independent of the platen and coöperative with said clamping member. 75
18. In a typewriting machine, the combination of a rotative platen, a plate at the discharge side of the platen and over which the paper is directed as it leaves the platen, and a spring-pressed hand-released pivoted clamping member coöperative only with said plate to hold one or more of a set of superposed sheets while another of said set is removed. 80
19. In a typewriting machine, the combination of a rotative platen, a plate at the discharge side of the platen and over which the paper is directed as it leaves the platen and which extends substantially throughout the length of the platen, and a spring-pressed clamping member coöperative only with said plate to hold one or more of a set of superposed sheets while another of said set is removed. 85
20. In a typewriting machine, the combination of a rotative platen, paper feeding devices, a separate independently-operating record-sheet clamping means arranged over the platen for holding one or more superposed sheets after they have been fed past the printing point, said clamping means being inactive during the feeding and writing operations and arranged to be inserted between the sheets and to clamp the lower sheets only after the termination of said feeding and writing operations. 90
21. In a typewriting machine, the combination of a rotative platen, and clamping means comprising a spring-pressed sheet holding device arranged over the platen and normally in disuse but adapted to be introduced between superposed sheets while said sheets are in the machine and to hold one or more of said sheets while another of said sheets is being removed. 100
22. In a typewriting machine, the combination of a rotative platen, paper feeding mechanism, a clamping means independent thereof and adapted only for holding certain of a series of superposed sheets at the discharge side of the platen during removal of one or more of said sheets, said clamping means comprising a clamping member arranged over the platen and coöperative with 110

certain of the work sheets, said clamping member being supported at one end only beyond or outside of the side edges of said sheets.

- 5 23. In a typewriting machine, the combination of a rotative platen, paper feeding mechanism, clamping means normally inactive while said paper feeding mechanism is active and adapted only for holding certain of the series of superposed sheets during the removal of one of said sheets, said clamping means comprising a clamping member arranged over the platen at the discharge side thereof and supported beyond and outside of the side edges of said sheets; and means for enabling an adjustment of said clamping member longitudinally of the platen.

24. In a typewriting machine, the combination of a rotative platen, paper feed devices, and clamping means separate from said paper feed devices for holding one sheet against movement circumferentially of the platen while another sheet is removed, said clamping means being arranged for use when the paper feed devices are not feeding the paper and comprising a pivoted spring-pressed clamping member arranged over the platen, the pivot of said clamping member being to one side of the sheets written upon and the axis thereof extending longitudinally in a plane at right angles to the axis of the platen.

25. In a typewriting machine, the combination of a rotative platen, and record-sheet clamping means comprising a clamping member mounted to swing in a plane which cuts through the platen longitudinally thereof.

26. In a typewriting machine, the combination of a rotative platen, and clamping means for holding certain of a series of superposed sheets, said clamping means comprising a clamping member pivoted at its outer end and extending inwardly toward the center of the platen at its free end and pivoted to swing in a plane that cuts through the platen longitudinally thereof.

27. In a typewriting machine, the combination of a rotative platen, a plate arranged above the platen and over which work sheets are adapted to pass as they leave the platen, and a clamping member pivoted at its outer end and extending inwardly at its free end toward the center of the platen and cooperative with said plate to hold certain of a series of superposed sheets while another of said sheets is being removed, said clamping member being pivoted to swing in a plane which cuts the platen longitudinally thereof.

28. In a typewriting machine, the combination of a rotative platen, and clamping means comprising a spring-pressed sheet holding device arranged over the platen and arranged to be placed between superposed

sheets when the platen is at rest and to hold against feeding one or more of said sheets while another of said sheets is being removed, means for enabling adjustment of said sheet holding device longitudinally of the platen, and a finger piece carried by said sheet holding device and by means of which it may be swung into and out of operative position.

5 29. In a typewriting machine, the combination with a rotatory platen, of a normally unapplied clamp arranged on the discharge side of the printing point and adapted to be inserted between the sheets of a pile of superposed sheets and hold against feeding the sheet or sheets underneath the clamp while permitting the sheet or sheets above the clamp to be removed.

29. In a typewriting machine, the combination with a rotatory platen, of paper feeding mechanism for a pile of sheets adapted to coöperate with the platen and to be cast off therefrom, and a clamping device separate from the paper feeding mechanism, said clamping device being at the discharge side of the platen and adapted to be inserted between sheets of the pile to hold against feeding one or more of the sheets when the paper feeding mechanism is cast off and enable the removal of one or more of the outer sheets.

30. In a typewriting machine, the combination with a rotary platen, of a paper table, paper feeding mechanism, and a paper clamping device fixed against movement in the direction of the feed of the work sheet, the arrangement being such that the paper is introduced to the platen between the paper table and the clamping device and such that the clamping device is brought into service after the cessation of the paper feeding operation and to prevent such an operation and coöperates with the paper at the side of the platen opposite the paper table.

31. In a typewriting machine, the combination with a rotative platen, the paper feeding devices of the machine and mechanism for holding a narrower record sheet against movement in the machine and on the platen while a superposed wider invoice sheet is removed therefrom, said mechanism comprising clamping means distinct from any of the paper feeding devices and arranged at the discharge side of the platen.

32. In a typewriting machine, the combination of a rotative platen; and mechanism for holding a narrower record sheet against movement in the machine and on the platen while a superposed wider invoice sheet is removed therefrom, said mechanism comprising means independently releasable at will and coöoperative only with the outside or wider invoice sheet, and means insertible and operating between the sheets to hold

said narrower inside record sheet during the removal of the outside wider invoice sheet, said last mentioned means being fixed against movement in the direction of the 5 length of the record sheet.

34. In a typewriting machine, the combination of a rotative platen; paper feeding devices; mechanism for holding a narrower record sheet against movement in the machine and on the platen while a superposed wider invoice sheet is removed therefrom, said mechanism comprising clamping means distinct from any of the paper feeding devices, said clamping means being arranged 10 on the discharge side of the platen, and means for affording an adjustment of said clamping means longitudinally of the platen.

35. In a typewriting machine, the combination of a rotative platen, means at the discharge side of the platen for holding the side edges of certain of a series of superposed sheets on the platen, and means also at the discharge side of the platen extending 20 intermediate said first mentioned holding means, for holding the inner of said superposed sheets while the outer sheet is removed from the machine, the second holding means acting between the superposed 25 sheets.

36. In a typewriting machine, the combination of a rotative platen, paper feeding

devices including means for holding a set of superposed sheets on the platen, and clamping means distinct from any of the 35 paper feeding devices of the machine, said clamping means being arranged above the platen and cooperative to hold stationary one or more of the inner sheets of the set of superposed sheets during the removal of 40 the outermost sheet.

37. In a typewriting machine, the combination of a rotative platen, paper feeding devices including means for holding a set of superposed sheets on the platen, said 45 holding means being normally in engaging position, and a normally disengaged paper clamping device distinct from any of the paper feeding devices of the machine, said clamping device being arranged at the discharge side of the platen and operative to clamp one or more of a set of superposed sheets after they leave the printing point to hold the same against movement while the outermost of said sheets is removed. 50

Signed at the borough of Manhattan, city of New York, in the county of New York, and State of New York, this 4th day of May A. D. 1908. 55

JACOB FELBEL.
